METHOD OF PRODUCING BOX OR CONTAINER PARTS HAVING A CURVED BOTTOM

Johannes Schmiedel, Dresden, Germany, assignor to the Firm Universelle Cigarettenmaschinen-Fabrik J. C. Muller & Co., Dresden, Germany

Application February 18, 1930, Serial No. 429,250,
and in Germany February 26, 1929

8 Claims. (Cl. 33—36)

This invention relates to improvements in the production of the parts of boxes or containers having a curved bottom.

In the production of boxes and particularly those which are provided with lids and with a neck insert it is usual to give the lid a convex curvature and also to provide it with impressions.

It has been proposed to form boxes first with a flat bottom and a flat lid, to open them after they are completed and in this condition to deliver them to a stamping press which produces the curvature of the bottom of the lid and the necessary impressions. This known method has the disadvantage that it involves changing the shape of the already completed box, an operation which with fragile articles does not produce a satisfactory product.

It has moreover been proposed to curve the blank as regards its bottom portion before production of the box and to apply the blank thus shaped to the completed under part and form it on this. This operation involves great difficulty because the shaping of the lid portion on the neck insert is naturally possible only when the lid portion is of fragile paper and the neck insert of strong cardboard.

As distinguished therefrom the present method consists in shaping a box blank already curved as regards its bottom portion in a shaping channel with the aid of a forming block adapted to be applied to the one side flap and having a shape corresponding to the curvature. In this way separate box or container parts or even complete boxes can be produced with and without neck inserts in one operation and the curvature of the portion of the bottom of the box in question produced in a satisfactory manner.

In apparatus intended for carrying the method into effect a pile of blanks is provided from which the blanks are delivered separately into a press for curving the bottom whereupon the blanks with the bottom now curved are placed in front of a shaping channel or in front of the forming block, the side of the shaping channel corresponding to the curved side of the forming block being mounted resiliently.

The invention is illustrated in the accompanying drawings in which

Fig. 1 is a vertical longitudinal section through the apparatus,

Figs. 2 and 3 show the shaping press in open condition in longitudinal and in cross section respectively,

Fig. 4 shows the rectangular shaping channel in section on the line 4—4 of Fig. 1,

Fig. 5 is a vertical cross section on the line 5—5 of Fig. 4,

Fig. 6 is a plan view of Fig. 1, the upper portion of the shaping press and the forming block guide being omitted,

Fig. 7 shows the blank with its finished shaped bottom part.

Fig. 8 shows in perspective the forming block employed.

Fig. 9 is a sectional elevation showing the relative position of the driving means about the subject matter of Fig. 1 of the drawings.

Fig. 10 is a detail longitudinal section showing the shaping press in open condition and including the blank feeding lug.

Fig. 11 is a section along line 11—11 of Fig. 12.

Fig. 12 is a sectional elevation similar to Fig. 4 showing in addition thereto actuating means for elements thereof.

Fig. 13 is a top plan view of the device shown in Fig. 9.

Fig. 14 is a view similar to Fig. 3 showing added details of the actuating mechanism for elements thereof.

Fig. 15 is a perspective view of the completed box.

Fig. 16 is a lateral sectional view of the completed box.

Referring to the drawings, the blanks Z_0 are fed from the pile 1 to the shaping station W by means of a lug 2' on the plunger 2. The shaping means consists of a matrix 3 and a hollow die 4 which after the blank is in position on the matrix presses on the side flaps of the blank. The shaping die 5 which is movable in the hollow die 4, now moves downwards and forms the lid portion with a curved surface as shown in Fig. 7. The lugs 6 provided on the plunger 2 now push the blank along the supporting bars 7 so that the front flap comes into position over the shaping channel 8. At the same time the blank Z_0 intended to form the lid portion is moved towards the blank forming the lid portion by means of the plunger 9 so that the two blanks meet midway over the shaping channel 8. After the neck strip Z_0 is placed above the junction of these blanks, the forming block F which is formed with a suitably curved surface and which in its inoperative position is pressed by a blade spring 10 against the abutment 11 is pushed downwards by means of the plunger 12. The forming block first contacts with the neck strip and presses it against the end flaps of the blanks located over the shaping channel, the resiliently supported counter-plunger 13 forming an abut-

ment 14.

ment. On further downward movement of the plunger 12 the plunger 13 is correspondingly moved backwards and the blanks are given a U-shape. In order to ensure that the lid portion 5 will fit properly around the curved lid forming block the left hand channel wall 14 is arranged to pivot at 15. A spring 16 bearing against the wall 14 presses the latter into the position shown in Fig. 1, the hook shaped lug 14' on the wall 10 14 bearing against a pin 17. On passage of the box part through the channel the plate 14 is pressed backwards. On the passage of the forming block with the work through the shaping channel 8 the four opposite side flaps are pressed 15 at the same time by the folding cam members 8', 8² against the forming block. After the forming block has moved with the work into the position shown in dotted lines in Fig. 4 a plunger 18 moves forward and pushes it into the channel 20 19 where in known manner the still projecting ends of the neck portion are folded by means of a suitably actuated projection 20 and by a folding finger 21 projecting into the shaping channel. The two upper side flaps strike against 25 bending bars 22 which bend these side flaps against the forming block. The work passes from the channel 19 the bottom of which is formed by a resilient plate 19' to a device which in known manner provides it with a binding 30 strip.

It should be noted that the one wall 19'' of the channel 19 is shaped to correspond to the curvature of the lid portion. It should also be noted that the plunger 2 as shown in Fig. 6 is provided 35 at its forward forked end with two lugs 6 which, at the time when the lugs 2' feed a new blank from the pile 1 to the shaping station W push the blank provided with its curved surface 1 forward on the supporting bars 7.

40 Actuation of the various movable elements of the device may be effected as follows:—

The lug 2' which feeds the blanks Z₀ from the pile 1 is actuated as follows:—

45 A link 23 is pivotally joined to arm 2 of said lug and one end of a lever 24. The latter is pivoted to the machine frame g at 25. The other end of lever 24 has a roller 26 which tracks a cam 27 keyed to a shaft 34 which is driven in a manner 50 to be presently described.

Lug 9 which feeds the blanks Z_u from the pile 1' is actuated as follows:—

55 A link 31 is pivotally connected to lug 9 and to one end of a lever 30 which latter is pivoted to the machine frame at 32. A link 28 is pivotally connected to lever 30 at 29' and to arm 24 at 24'. In this manner motion of both lugs is accomplished by a single cam. It is, of course, understood that lugs 2 and 9 are guided horizontally 60 in suitable manner.

Matrix die 3 is reciprocated vertically as follows:—

The matrix has a roller 36 mounted on an extension which tracks a cam 46 keyed to a shaft 41.

65 Die 5 is actuated as follows:—

The upper end of said die has two rollers 43 and 44 pivoted thereto in spaced relationship and between the said rollers a cam 42 is borne 70 on a shaft 45 to which it is keyed.

Cams 42 and 46 are driven by means of a sprocket chain 36' which passes over sprocket wheels 37, 38 and 35 keyed respectively to shafts 41, 45 and 34.

75 The plunger 12 which is slidably borne in a

guide 48 on an extension of the machine frame is actuated as follows:—

A lever 50 pivotally engages projection 12' on plunger 12 by means of a forked end 50'. Said lever is pivoted to the machine extension at 49. A link 51 is pivotally connected to lever 50 intermediate its ends and also pivotally connected to a lever 53. The latter is pivoted at 52 to the machine frame. Intermediate its ends said lever 53 has a roller 54 which tracks a cam 55 keyed on shaft 34.

80 Plunger 13 which is slidably borne in guides 61 having a spring 62 between guide 61 and its head, to retain it in raised position, and a lateral projection 13' at the lower end of the lower guide 61 to prevent it from being moved completely out of guides 61, is actuated as follows:—

85 A lever 60 is pivotally mounted at 59 to the machine frame. One end 60' of said lever engages the projection 13'. The other end of said lever is provided with a roller 60² which tracks a cam 58 keyed on a shaft 57.

90 Suitable gearing 56 connects shafts 57 and 35 and either of the two may be driven from a source not shown.

95 Plunger 18 which is slidably borne in the machine frame is actuated as follows:—

100 A link 80 is pivotally connected to said plunger and to one end of a lever 78. The latter is pivotally intermediate its ends at 79 to the machine frame. The free end of said lever has a cam roller 81 which tracks a cam groove 77' in a cam 77 keyed to shaft 57.

105 Finger 20 which is slidably borne on plunger 18 is actuated as follows:—

110 A link 72 pivotally engages said finger and one end of a lever 73. The latter is pivotally mounted to the machine frame at 74. The free end of said lever has a roller 75 which tracks a cam groove 76' in a cam 76 keyed to said shaft 57.

115 I claim:

120 1. A method of producing box or container parts having a curved face consisting in folding a box blank already curved as regards a portion thereof about a forming block having a wall whose shape corresponds to the curved portion of said blank.

125 2. Apparatus for producing box or container parts having a curved face from box blanks comprising a shaping press to curve a portion of each of said blanks, means for feeding said blanks separately from a pile of blanks into said shaping press, a shaping channel, a forming block having a curved wall, means for feeding said curved 130 blanks from said press in front of said shaping channel, said shaping channel formed with a curved wall corresponding to the curvature of said forming block wall and being resiliently mounted, and means for moving said curved blank and block through said channel to fold the blank about said block.

135 3. Apparatus for producing box or container parts having a curved face from box blanks comprising a shaping press to curve a portion of each of said blanks, means for feeding said blanks separately from a pile of blanks into the shaping press, a shaping channel, a forming block having a curved wall, means for feeding said curved 140 blanks from said press in front of said shaping channel, said shaping channel formed with a curved wall corresponding to the curvature of the forming block and being resiliently mounted, means for moving said curved blank and said block through said channel to fold the blank 145 150

about three edges of said block and the curved face, a second channel formed with a wall recessed to correspond to the curvature of the bottom, and means for moving said block and partially folded blank through said second channel to complete the folding of said blank about said block.	5	tion in front of said shaping channel, a forming block having a curved wall to correspond to the curve imparted to said blank, said shaping channel being formed with a resiliently mounted curved wall corresponding to the curvature of said forming block wall and means for moving said forming block together with said curved blank through said shaping channel to partially fold said blanks about said block and means to complete the folding of said blank about said block.	80
4. A method of producing a box part having a curved face from a blank, including the step of curving a portion of said blank and then folding said blank about a forming block having a curved wall to conform with that of said blank, said curved portion being folded onto said curved wall.	10	7. Apparatus for producing a box part having a curved wall from a box blank comprising means to curve a portion of said blank including a sloping channel and means to fold said curved blank into box shape.	85
5. A method of producing a box having a curved face from two box blanks, comprising curving a portion of one of said blanks and then simultaneously folding both blanks about a forming block having a curved wall to conform with that of said previously curved blank, said curved portion being molded onto said curved wall.	15	8. Apparatus for producing a box part having a curved wall from a box blank comprising means to curve a portion of said blank, a forming block having a curved wall to correspond to the curve imparted to said blank and means to fold said blank about said block into box shape, said curved portion of said blank being adapted to coincide with the curved wall of said block.	90
6. Apparatus for producing a box part having a curved wall from a box blank comprising a shaping press for curving a portion of said blank, means for feeding blanks separately from a pile to said press, a shaping channel, means for feeding said curved blanks from said press to a posi-	20		95
